(57) **CLAIM**

The ornamental design for a Christmas watering device, as shown and described.

DESCRIPTION

FIG. 1 is an environmental first perspective view of the design of this invention.

FIG. 2 is a second perspective view;

FIG. 3 is a first side view;

FIG. 4 is a second side view;

FIG. 5 is a third side view;

FIG. 6 is a fourth side view; and,

FIG. 7 is a top view; and,

FIG. 8 is a bottom view.

The broken lines represent environment and form no part of the claimed design. The material of the stem is flexible.

1 Claim, 4 Drawing Sheets

FIG. 2

FIG. 1

FIG. 3

FIG. 4

FIG. 5

FIG. 6

FIG. 7

FIG. 8
